(57) **CLAIM**

The ornamental design for a socket, as shown and described.

DESCRIPTION

FIG. 1 is a top view of a first embodiment of a socket, showing our new design;

FIG. 2 is a left side view thereof;

FIG. 3 is a right side view thereof;

FIG. 4 is a bottom view thereof;

FIG. 5 is a front view thereof;

FIG. 6 is a rear view thereof; and

FIG. 7 is a perspective view thereof.

FIG. 8 is a top view of a second embodiment of a socket, showing our new design;

FIG. 9 is a left side view thereof;

FIG. 10 is a right side view thereof;

FIG. 11 is a bottom view thereof;

FIG. 12 is a front view thereof;

FIG. 13 is a rear view thereof; and,

FIG. 14 is a perspective view thereof.

The broken line portion of the figure drawings is included to show portions of the article that form no part of the claimed design.

1 Claim, 14 Drawing Sheets
